BATHING CAP

William D. Timmons, Coshocton, Ohio, assignor
to Pretty Products, Inc., Coshocton, Ohio, a cor-
poration of Ohio

Application November 1, 1949, Serial No. 124,793

3 Claims. (Cl. 2—68)

1

This invention relates to the art of bathing caps.

It has of course always been desirable for a bathing cap to prevent the entrance of water thereunder so as to keep the user's hair dry; and there have been various attempts to produce such a cap. However, there appears to have been experienced considerable difficulty because of the fact that in applying the cap to the head of the user, it is pulled in a direction transverse to that of normal engagement of the sealing means that is provided upon the inner surface of the cap and such transverse pulling of the sealing means has seriously interfered with its assuming proper position for effective sealing engagement.

Accordingly, the object of the present invention is to devise a bathing cap with sealing means upon the inside thereof that will permit application of the cap to the head of the user in the usual manner and at the same time will ensure effective engagement of the sealing means with the head of the user.

More specifically, my object is to devise a bathing cap with such a sealing means that will respond to the usual pulling or stretching action during application of the same to the user's head and will at once resume normal effective condition for most effective sealing engagement upon release of the same when such pulling stretching action has been completed and the cap has been placed in the desired position.

Other objects will appear from the following description and claims when considered together with the accompanying drawing.

Fig. 1 illustrates, in side elevation, the present bathing cap in position upon the head of the user and with a portion of the same turned back so as to expose my improved sealing means;

Fig. 2 is an enlarged view of a portion of my improved sealing means; and

Fig. 3 is a sectional view taken on either line 3—3 of Fig. 1 or line 3—3 of Fig. 2.

It is to be understood that the present form of disclosure is merely for the purpose of illustration and that there might be devised various modifications thereof without departing from the spirit of my invention as herein set forth and claimed.

Referring now to the accompanying drawing in detail, the cap 1 of rubber or rubber-like material is provided upon the inner surface thereof, near the edge, with my improved sealing means which forms an integral part of the cap itself; and this sealing means extends entirely about the edge portion of the cap. The rubber or rubber-

like material of the cap 1 is such that it is well suited for the purpose of sealing the head of the user and this art is described in my application No. 124,793 filed on November 1, 1949, and is entitled "Rubber Bathing Cap".

Referring now to Fig. 1, the cap 1 is shown in side elevation with its inner surface 2 facing the user.

Referring now to Fig. 2, the improved sealing means is shown in enlarged view and is indicated by the reference numeral 3.

Referring now to Fig. 3, the improved sealing means is shown in cross section and is indicated by the reference numeral 4.

2

like material of the cap being of a resilient nature, the sealing means is also resilient, as will be explained.

This sealing means, in the present illustration, consists of a cloven or double middle rib 2 and the single ribs 3 and 4 which extend along opposite sides of the middle rib 2 and in parallel relation thereto. All of these ribs 2, 3 and 4 project inwardly from the inner surface of the bathing cap and, under normal conditions, occupy position substantially normal to the surface of the cap. Each of these ribs may be of tapered or wedge form, as clearly indicated in Fig. 3 of the drawing.

Along the inside of each of the ribs 3 and 4 I have provided buttresses 3a and 4a, respectively, which extend in a direction normal to their ribs and are inclined away therefrom after the manner of a mechanical buttress. These buttresses are formed integrally with the cap and ribs and are hence of a resilient nature.

Also, upon opposite sides of the middle rib 2 I have provided the integral buttresses 2a which are of the same form as the buttresses 3a and 4a. The buttresses 2a upon the opposite sides of the rib 2 are arranged opposite each other and are staggered with respect to the buttresses 3a and 4a which are located opposite each other. Also, as clearly indicated in Fig. 2 of the drawing, the staggered buttresses extend into the opposite spaces between the opposite row of buttresses in each instance; but all of the buttresses of one rib terminate decidedly short of the opposite rib, with the result that the buttresses of each of the ribs 3 and 4 act independently of the buttresses 2a of the middle rib. The ribs may be all of the same height and the ribs 3 and 4 are of duplicate form and dimensions. Also, all of the buttresses of the several ribs may be of the same form and dimensions, and the buttresses are of less depth or height than the ribs at the points where they join the ribs.

Except for my particular sealing means, as herein described, the bathing cap in all other respects may be of the same form as the familiar bathing cap, including the strap 5 which has its one end attached to one side of the cap and is adapted to extend beneath the user's chin and to have snap engagement at its other end with the other side of the cap, as indicated in Fig. 1 and as will be readily understood.

Such a cap will of course have a close fit upon the head of the user and it will be pulled over the head in the same manner as the familiar rubber bathing cap. During such application

of the cap, the ribs 2, 3 and 4 will be flexed towards flattened condition against the resistance of their buttresses, the buttresses 3a and adjacent buttresses 2a being compressed and the buttresses 4a and adjacent buttresses 2a being stretched, so that all of the buttresses are temporarily deformed while pulling the cap onto the head to the proper position. Then, when the cap has been fully placed upon the head and released, the natural tendency of the buttresses to again assume their normal condition, will cause their respective ribs to return to upright condition, that is substantially normal to the body of the cap and the head of the user; and the entire action of each rib during its temporary deformation and return to normal condition will be entirely independent of that of the other ribs by virtue of the independent arrangement of the buttresses of each rib, as above explained.

Thus, in the event that the cap fits the user's head so tightly that one of the several ribs might not return completely to its normal condition upon release of the same, such binding of the one rib will not affect the other ribs which, because of the independent action of their buttresses, will be permitted to respond to the flexing of their buttresses and to be returned thereby to normal condition for most effective sealing. The result is that, with the several ribs and their independently acting buttresses, there is ensured a water-tight seal between the marginal portion of the cap and the head of the user and consequently there is no danger of leakage. Furthermore, by virtue of the resilient nature of the cap body and the integrally formed separate ribs with their individual and separate and independently acting buttresses, this sealing means will be self-accommodating to the shape of the head of the user so as to still further ensure water-tight engagement at all points. That is to say, my improved sealing means is self-accommodating in a most complete and effective manner.

Other advantages, resulting from my present improvement, will readily suggest themselves to those who are familiar with the art to which this invention relates.

What I claim is:

1. A bathing cap of resilient rubber-like material having its inner surface provided with integral inwardly extending parallel spaced resilient sealing ribs near the edge thereof and provided

also with separate resilient integral buttresses extending substantially normal to and connected independently of each other with the adjacent sides of said ribs, the buttresses of one of said ribs extending in opposite direction and towards and being staggered with respect to those of another rib, so as to permit flexing action of said ribs independently of each other.

2. A bathing cap having its inner surface provided with a plurality of inwardly extending parallel spaced resilient sealing ribs near the edge thereof including a middle double rib and a rib upon each side thereof, and said cap being provided also with separate resilient buttresses extending substantially normal to and connected independently of each other with the sides of said ribs, the buttresses upon the sides of the middle rib being opposite each other, and the buttresses of the respective sides of the outer ribs adjacent the middle rib being opposite each other and in staggered relationship with respect to the buttresses of the middle rib, so as to permit flexing action of said ribs independently of each other.

3. A bathing cap of resilient rubber-like material having its inner surface provided with a plurality of integral inwardly extending parallel spaced resilient sealing ribs near the edge thereof including a middle double rib and a rib upon each side thereof, and said cap being provided also with separate resilient integral buttresses extending substantially normal to and connected independently of each other with the sides of said ribs, the buttresses upon the sides of the middle rib being opposite each other, and the buttresses of the respective sides of the outer ribs adjacent the middle rib being opposite each other and in staggering relationship with respect to the buttresses of the middle rib, so as to permit flexing action of said ribs independently of each other.

WILLIAM D. TIMMONS.
